UNITED STATES PATENT OFFICE.

WILLIAM M. VENABLE, OF PITTSBURGH, PENNSYLVANIA, ASSIGNOR TO BLOW STEEL CONSTRUCTION COMPANY, OF PITTSBURGH, PENNSYLVANIA, A CORPORATION OF NEW JERSEY.

BEAM AND GIRDER MOLD.

1,171,760.

Specification of Letters Patent.

Patented Feb. 15, 1916.

Application filed February 20, 1915. Serial No. 9,515.

To all whom it may concern:

Be it known that I, WILLIAM MAYO VENABLE, a citizen of the United States, residing at Pittsburgh, in the county of Allegheny and State of Pennsylvania, have invented certain new and useful Improvements in Beam and Girder Molds, of which the following is a specification.

The invention relates to beam and girder molds, and particularly to the mold construction at the intersection of a girder and beam. The invention has for its primary objects, the provision, in a construction of the kind specified, of an improved adjustable corner connection; the provision of a lap corner connection for beams and girders arranged to give any and every adjustment which conditions may require; and the provision of a corner connection of the kind specified, so arranged as to permit of a most ready and convenient assembling and disassembling of the mold parts. One embodiment of the invention is illustrated in the accompanying drawings wherein—

Figure 1 is a perspective view showing my improved construction; Fig. 2 is a plan view of the apparatus with some of the parts broken away; and Fig. 3 is a section on the line III—III of Fig. 2.

Referring to the drawings; 1, 2, 3 and 4 are a number of the panels which go to make up a girder; 5 and 6 are a pair of opposing beam panels; 7 and 8 are lap corner panels connecting the girder and beam panels; 9 is a girder splice plate; 10 is a girder connecting bar; 11 and 12 are shores for supporting the girder from beneath; and 13 and 14 are the planks constituting the bottom members of the girder and beam, respectively.

Both the girder and beam panels are provided at their upper and lower edges with outwardly turned flanges as illustrated, and the lap corner panels are provided at their upper edges only with outwardly turned flanges and overlapping the flanges of the panels. The girder panels are provided with pairs of vertical stiffening angles 16 and 17 placed intermediate the ends of the panels and with other vertical angles 18 and 19 at the ends of the panels, such latter angles having their flanges perforated and serving as connection means with the next adjacent panels. Opposing girder panels, such as 1 and 2, are connected together by

means of gage plates 20 and 21 which serve to hold the panels in parallelism, the ends of the gage plates being secured by means of pins 22. The beam panels 5 and 6 are similar to the girder panels 1 and 2 except their depth is less, such beam panels being only of the depth of the lap corner panels 7 and 8.

The means by which the lap corner panels are secured adjustably to the beam and girder panels will be seen by reference to Figs. 2 and 3 in connection with Fig. 1. The connections for the panels 7 and 8 are similar so that a description of one will suffice for both.

As indicated in Fig. 2, the vertical end edges of the panels 2 and 5 are provided with angles 23 and 24, such angles being similar to the angles 18 and 19 illustrated in Fig. 1. Bolted to the flanges of these angles are the angles 25 and 26, the free wings of which, as indicated in Fig. 3, are provided with a plurality of horizontal slots 27. See also similar angle 25 with slots 27 at left hand end of panel 2 in Fig. 1. The lap corner panel 7 is provided with a plurality of rows of holes 28 (Fig. 1) and this panel is secured to the angles 25 and 26 by means of stove bolts 29 which extend through the holes in the lap corner panel and through the slots 27 in the wings of the angles 25 and 26. This arrangement gives any and all desired adjustments since the slots 27 in the arms or flanges of the angles 25 and 26 lying next the lap plates 7 give adjustments lying between the holes in the rows 28.

Lying below the panels 7 and 8 and serving to connect the girder panels 2 and 4 is the girder splice plate 9 having at its lower edge an inwardly turned flange 30. This splice plate is provided with rows of holes 31 and stove bolts 32 extending through such holes and through the lower slots 27 in the angles 25 serve to connect the splice plate adjustably at each end to the girder panels 2 and 4, the adjustment being precisely the same as that secured between the panels 7 and 8 and the girder and beam panels. This arrangement permits of the use of standard panels throughout the construction, the adjustment secured in the use of the lap corner panels taking care of all odd distances.

The splice plate 30 is provided at its up-

per edge with an outwardly extending bracket, such bracket being in the form of the angle 33 (Figs. 1 and 3). This bracket serves as a supporting member for the end of the beam.

5 In the erecting operation the parts of the girder are secured together in their lower position, the bars 10 being used at the breaks in the girder at which beams are to intersect. The girder is then raised to position and supported by means of the shores 11 and 12. The beams are then assembled with the lap corner panels secured thereto and placed in the position illustrated with 10 the ends of the beams resting on the brackets 33 carried by the splice plates 9, the bars 10 being removed at such time.

15 The advantage of the construction lies in the fact that it may be very readily assembled and disassembled. The construction may be used with different spacing of beams and with beams of any height or width, any desired adjustment of the parts may be secured by the use of the lap corner panels 20 and splice plates, and a very secure and effective connection is secured at the intersection of the beams and girders. Other advantages incident to the construction will be readily apparent to those skilled in the 25 art.

30 What I claim is:

1. In combination, a pair of alined girder panels with their ends spaced apart, a pair of opposing beam panels at right angles to the girder panels of less depth than such 35 girder panels with their ends adjacent the space between the girder panels, a pair of lap corner panels each having a pair of wings which are at right angles to each other and overlap the inner faces of the girder and beam panels, and a girder splice plate 40 overlapping the inner faces of the girder panels and lying beneath the lap corner panels.

45 2. In combination, a pair of alined girder panels with their ends spaced apart, a pair of opposing beam panels at right angles to the girder panels of less depth than such girder panels with their ends adjacent the 50 space between the girder panels, a pair of lap corner panels each having a pair of wings which are at right angles to each other and overlap the inner faces of the girder and beam panels, a girder splice plate overlapping the ends of the girder panels and lying 55 beneath the lap corner panels and the beam, and a supporting bracket for the beam panels secured to the outer face of the girder splice plate and projecting beneath the lap corner panels.

60 3. In combination, a pair of alined girder panels with their ends spaced apart, a pair of opposing beam panels at right angles to the girder panels of less depth than such 65 girder panels with their ends adjacent the

space between the girder panels, a pair of lap corner panels each having a pair of wings which are at right angles to each other and overlap the inner faces of the girder and beam panels, and a girder splice plate 70 overlapping the inner faces of the girder panels and lying beneath the lap corner panels, the said splice plate extending down to the lower edges of the girder panels.

4. In combination, a pair of alined girder panels with their ends spaced apart, a pair of opposing beam panels at right angles to the girder panels of less depth than such girder panels with their ends adjacent the space between the girder panels, a pair of 75 lap corner panels each having a pair of wings which are at right angles to each other and overlap the inner faces of the girder and beam panels, a girder splice plate overlapping the inner faces of the girder panels and lying beneath the lap corner panels, means whereby the lap panels are secured adjustably to the girder and beam panels, and means whereby the splice plate 80 is secured adjustably to the girder panels. 90

5. In combination, a pair of alined girder panels with their ends spaced apart, a pair of opposing beam panels at right angles to the girder panels of less depth than such girder panels with their ends adjacent the 95 space between the girder panels, a pair of lap corner panels each having a pair of wings which are at right angles to each other and overlap the inner faces of the girder and beam panels, and a girder splice plate 100 overlapping the inner faces of the girder panels and lying beneath the lap corner panels, the said lap corner panels having adjustable connections with the beam and girder panels, and the girder splice 105 plate having adjustable connections at its ends with the girder panels.

6. In combination, a girder panel having a vertical flange at its end, a beam panel at right angles to the girder panel and having 110 a vertical flange at its end, a vertical ninety degree angle secured detachably to each of the said flanges along one of its flanges and having its other flange perforated, a lap corner panel having a pair of wings which 115 overlap the inner faces of the girder and beam panels, the said wings each having a plurality of perforations, and means adapted to extend through the perforations in the angles and panels for securing such parts 120 adjustably and detachably together.

7. In combination, a girder panel having a vertical flange at its end, a beam panel at right angles to the girder panel and having a vertical flange at its end, a vertical ninety 125 degree angle secured detachably to each of the said flanges along one of its flanges and having a plurality of horizontal slots in its other flange at varying heights, a lap corner panel having a pair of wings which 130

overlap the inner faces of the girder and provided with a plurality of horizontal rows of closely spaced holes at varying heights, and bolts for extending through the said 5 slots and holes for securing the lap panel to the slotted flanges of the angles.

8. In combination, a pair of alined girder panels with their ends spaced apart, a pair of opposing beam panels at right angles to the 10 girder panels of less depth than such girder panels with their ends adjacent the space between the girder panels, a pair of lap corner panels each having a pair of wings which are at right angles to each other and overlap the inner faces of the girder and beam panels, and a girder splice plate overlapping the inner faces of the girder panels and lying beneath the lap corner panels, the said girder and beam panels having vertical 15 detachable angles at their ends, and the said lap corner plates having adjustable connections with the said angles. 20

9. In combination, a pair of alined girder panels with their ends spaced apart, a pair of

opposing beam panels at right angles to the 25 girder panels of less depth than such girder panels with their ends adjacent the space between the girder panels, a pair of lap corner panels each having a pair of wings which are at right angles to each other and overlap the inner faces of the girder and beam panels, and a girder splice plate overlapping the inner faces of the girder panels and lying beneath the lap corner panels, the said 30 girder and beam panels having vertical detachable angles at their ends, and the said lap corner plates having adjustable connections with the said angles, and the girder splice plate also having adjustable connections with said angles on the girder panels. 35 40

In testimony whereof I have hereunto signed my name in the presence of the two subscribed witnesses.
